STOCK REEL

Filed Dec. 12, 1946

INVENTOR
William B. Retz
BY
Matthew Beckett
ATTORNEYS.

the reel has been leveled with the machine 5 and the stock tubes are in exact axial alignment with the spindles, bar stock of maximum size may be carried by the stock tubes and spindles and will rotate without whipping. Now, if smaller bar stock is to be employed, it will be apparent that with the stock tubes in axial alignment with the spindles, the stock supported in the reel would tend to sag and during rotation of the bar stock by the spindles there would likely be substantial whipping of the stock, with consequent excessive noise, wear, and vibration. When bar stock of smaller diameter is to be operated on the reel is raised so that the bar stock will rest naturally in the bottom of the stock tubes in substantially exact alignment with the spindles in which position the bar stock tends to rotate properly without substantial tendency toward whipping. Heretofore, the stock reel could be raised so as to position the smaller diameter bar stock properly by individual adjustment such as by means of the nuts 25-30. However, individual adjustment of the nuts 25-30 created a danger of raising or lowering one end or the other of the stock reel too much or too little, with consequent misalignment effects.

I provide means for quick and easy raising or lowering of the entire stock reel so as to position the same for proper alignment of bar stock of any size accurately with the spindles. In the form illustrated, I employ cam means at each of the two spaced supports of the stock reel and so interconnect the cam means that actuation of one automatically causes actuation of the other so that the stock reel if once level may be raised or lowered at will without disturbing the level of the reel. In the form illustrated, the plates 20-21, which are in effect merely parts of the sleeves 22-23, are provided with one or more inclined or cam surfaces 34 for receiving cam followers which may be corresponding cam surfaces 35 on the plates 18-19. The two plates may be connected as by means of a link 36 pivotally connected to each plate so that when one plate is turned through a certain angle, the other plate will be turned through a corresponding angle. Since the cam surfaces may be and preferably are identical, both ends of the reel will be raised or lowered equal amounts. Thus, with little effort and without danger of disturbing the level of the reel, the latter may be raised or lowered so as to accommodate itself to bar stock of any desired diameter. One of the plates, for example the plate 19, may be locked in adjusted position and, in the form shown, the plate 19 is provided with a slot 37 for receiving a clamping screw 38 screwed into a part 39 of the bracket secured to the frame of the machine. The plate 19 may carry indicia to indicate the height which the spindle carrier has been raised or lowered by the cam means. Such indicia preferably will be in terms of bar stock diameter as indicated roughly in Fig. 2.

It will be clear, then, that when it is desired

to raise or lower the stock reel, the clamping screw 38 is loosened and the cam plate 19 rotated by means of the handle 40 until the cams raise the stock reel or lower the same the amount desired. When the stock reel is properly positioned, the clamping screw 38 may again be tightened so as to hold the stock reel in the desired position. It will thus be seen that I have provided improved means for moving the stock reel so as to accurately position bar stock in axial alignment with the spindles of the machine.

While the invention has been described in connection with a multiple spindle machine and with a stock reel employing stock tubes corresponding in number to the spindles of the machine, it is to be understood that for a single spindle machine the single stock tube required could be raised or lowered in accordance with my invention, and I desire the term "stock reel" to apply to means for carrying a single stock tube or a plurality of stock tubes.

While the invention has been described in considerable detail and a preferred form illustrated, it is to be understood that various changes may be made within the scope of the invention as defined in the appended claims.

I claim:

1. A stock support comprising an elongated stock reel for supporting bars of stock to be fed into an automatic lathe or the like, supports for the ends of said reel, individually adjustable mounting means for said supports whereby said reel may be leveled and aligned relative to said lathe spindles, cam means positioned between said mounting means and said supports, and a common actuating means for said cam means, whereby said reel may be additionally aligned relative to said lathe spindles for different sizes of stock with a single operation.
2. A stock support as defined in claim 1, wherein in said actuating means includes a clamping means for retaining said cam means in adjusted position.
3. A stock support as defined in claim 2, wherein in said actuating means further include indicating means corresponding to the stock sizes for determining said adjusted position.

WILLIAM B. RETZ.
